UNITED STATES PATENT OFFICE.

WILLIAM H. GREENE, OF LOWELL, MASSACHUSETTS.

CARPENTER'S RULE.

SPECIFICATION forming part of Letters Patent No. 325,533, dated September 1, 1885.

Application filed October 4, 1884. (Model.)

To all whom it may concern:

Be it known that I, WILLIAM H. GREENE, a citizen of the United States, residing at Lowell, in the county of Middlesex and Commonwealth of Massachusetts, have invented a new and useful Improvement in Carpenters' Rules, of which the following is a specification.

My invention relates to carpenters' rules; and it consists in devices and combinations, to hereinafter described and claimed, wherein such rules are made to serve (in addition to their ordinary purposes) as gages, squares, and bevels.

In the accompanying drawings, Figure 1 is an isometric view of my improved folding rule, a part of one of the legs being broken off and the remaining part being turned at right angles to the other leg to form a square; Fig. 2, an isometric view of said rule, the legs being folded or closed, and one leg being moved along on the other to form a gage. Figs. 3 and 4 are partly sections on the line Y Y in Fig. 5, but the grooved leg and the plates are shown in elevation, the legs being locked in position 25 in Fig. 3 and unlocked in Fig. 4; Fig. 5, a section on the line X X in Fig. 1; Fig. 6, an isometric view of the binder detached; Fig. 7, an isometric view of the wedge detached.

The legs A' A² of the rule A are of the usual construction, except that one of them, A², is provided, preferably on each side, with a longitudinal groove, a', running nearly from end to end thereof, and the other is cut away at a to admit the head b of the wedge B when the legs 35 are folded together.

The legs A' A² of the rule are marked in the usual manner with divisions of inches and fractions of inches.

The joint C is peculiar. The usual pieces, 40 c c, which form in effect a slot at the end of one leg, (into which slot the end of the other leg is inserted in the ordinary rule-joint,) being retained, but placed (and secured by the usual rivets) on the faces of the leg A', instead of 45 being flush therewith. Said pieces c c are thicker than usual, and have circular cavities c' c' on their inner faces, concentric with the circular ears c² c² on said pieces c c. Within these circular cavities are placed, on each side 50 of the leg A', thin or sheet-metal plates D D, in form segments of circles, the straight edges of which are turned inward at d d, at right

angles along a line parallel with the cords of such segments and enter the longitudinal grooves a' a'.

A wedge, B, as wide as the thickness of the leg A² and the plates D D combined, (except at b' b', where it is notched or provided with a neck,) is placed flatwise against the inner edge of the leg A², the side edges of the body 60 of the wedge being within said cavities c' c', and the necks b' b' of the wedge filling the space between the thick edges of the ears c² c². The neck of the wedge is long enough to allow the body of the wedge to move end- 65 wise within said cavities c' c'. The thick end or head b of the wedge has a cross-rib, b², on the side away from the leg A², by which the wedge may be moved slightly by placing the thumb-nail against said rib.

Between the pieces c c, on the other face of the wedge from the leg A², is a binder, F, which may be a segment of a short solid cylinder, but is preferably a steel spring bent as shown, having a straight flat side, f, which 75 presses against the wedge B, and a curved side, f', of the same radius as the outer curved surface of the ears c² c², except that the edges of the curved part of said spring are reduced at f' to enter and fit the circular cavities c' c', 80 and to form shoulders f² at the same distance from each other as the ears c² c², and which rest against said ears.

The ends of the spring F, when the same is not compressed, do not touch each other, 85 there being a small space at f' between them.

When the wedge B is crowded into the joint, as shown on Fig. 3, the spring or binder F is compressed, bringing its ends in contact, closing the space f', and pressing the curved surfaces of the binder F and of the plates D D outward, and so firmly against the curved inner walls of the cavities c' c' that said binder and plates will be prevented from turning in said cavities by friction, and thereby prevent the legs of the rule from turning on the joint C.

When the wedge is loosened—that is, drawn to the position shown in Fig. 4—the legs may easily be opened or closed, the ears turning 100 with the leg A' (to which they are secured, as above stated) and the plates D D, the wedge B and binder F turning with the leg A². It will be seen, also, that when the wedge

is loosened the plates D D may be moved along on the leg A², the bent edges of said plates D D sliding in said grooves a' a'; but that when the wedge is in the position shown 5 in Fig. 3 the part of the leg A² between the grooves a' and the wedge B will be pinched between said wedge and the turned-down parts d d of the plates D D, and the legs cannot slide on each other.

10 When the leg A' is moved along on the leg A² for some distance and is then turned or opened until the joint end of said leg strikes the inner edge of the leg A², as shown in Fig. 1, the two legs will be at right angles to each 15 other, and, after locking them by pushing in the wedge, the rule may be used as a square. In the same way the legs may be turned or opened to any smaller angle and there fastened, when the rule may be used as a bevel. 20 When the rule is closed, the depth of a mortise or hole may be measured by resting the end of the grooved leg on the surface of the timber at the edge of such mortise or hole and moving the other leg along on said grooved 25 leg, as shown in Fig. 2, until the grooved leg A' touches the bottom of said hole. In the same way one may measure the thickness of a molding, the height of a step or stair, or the like, allowing in each case the free end of the 30 leg A' to project beyond the free end of the grooved leg A².

When the legs are in the position shown in Fig. 2, a pencil may be placed at the free end of the leg A', and a line may be drawn parallel to the edge of a board by allowing the free 35 end of the leg A² to be in contact with the edge of such board while such line is being drawn.

The width of an opening may be measured by setting the square part of the joint end of 40 the leg A² against one side of said opening and then sliding the leg A' until the free end of said leg A' touches the other side of the opening.

I claim as my invention—

1. The combination of a leg, plates secured 45 thereto having ears provided with circular cavities concentric therewith, another leg, and plates adapted to enter said cavities and to turn

therein and to engage with and slide upon said last named leg, as and for the purpose specified.

2. The combination of a leg, plates secured thereto having ears provided with circular cavities concentric therewith, another leg, segmental plates adapted to enter said cavities and turn therein and to engage with and slide upon said last-named leg, the segmental binder placed within said cavities, and means, substantially as described, for crowding apart said binder and said segmental plates and forcing them outward against the curved inner walls of said cavities, to prevent said legs from turning on each other, as and for the purpose specified. 55

3. The combination of a leg, plates secured thereto having ears provided with circular cavities concentric therewith, another leg, segmental plates adapted to enter said cavities and turn therein and to engage with and slide upon said last-named leg, the segmental binder placed within the said cavities, and the wedge placed between said binder and said segmental plates 60 and adapted to be crowded between said binder and said segmental plates and to prevent said legs from turning on each other, as and for the purpose specified. 70

4. The combination of a leg, plates secured thereto having ears provided with circular cavities concentric therewith, another leg, segmental plates adapted to enter said cavities and turn therein and to engage with and slide upon said last-named leg, the binder, its edges entering 80 said cavities and provided with a spring, and the wedge placed between said binder and said segmental plates and adapted to be crowded between said binder and said segmental plates and to prevent said legs from turning on each other, as and for the purpose specified. 85

5. A rule having legs united at their ends by a joint and adapted to slide and turn one upon the other in the same plane, as and for the purpose specified.

WILLIAM H. GREENE.
